UNITED STATES PATENT OFFICE.

WILLIAM E. SWEET, OF DOWAGIAC, MICHIGAN.

LUBRICATOR.

SPECIFICATION forming part of Letters Patent No. 542,118, dated July 2, 1895.

Application filed October 18, 1894. Serial No. 526,830. (No model.)

To all whom it may concern:

Be it known that I, WILLIAM E. SWEET, of Dowagiac, county of Cass, State of Michigan, have invented certain new and useful Improvements in Lubricating Devices, of which the following is a specification; reference being had to the accompanying drawings.

The object of my invention is to provide a device for oiling a plurality of journal-bearings from a single point and which is preferably automatically operated by the movement of the machine. While especially designed for use in oiling exposed machinery, such, for example, as windmills, it is well adapted for use with other machinery.

In the accompanying drawings, Figure I is a central vertical section of my oil-receptacle as applied to a windmill, some of the parts being shown in elevation, the valve-trip being shown in the valve-operating position in full lines and shown out of position in dotted lines. Fig. II shows a part of the mechanism illustrated in Fig. I, showing means of conducting a lubricant from the receptacle to a particular class of bearings, shown as crank-bearings. Fig. III is a detached view showing the special auxiliary valve mechanism designed to be employed with crank-bearings.

Referring to the figures on the drawings, 1 indicates a suitable receptacle, preferably of oblong cylindrical shape, and having a conical cap 2 covering the entire top of the receptacle and secured to it, preferably by screw-threads 3. The conical shape and area of the cap is designed to shed water and protect the contents of the receptacle. The receptacle is supported in position by suitable means, as, for example, a bracket-support 4, suitably secured in place, as upon a windmill-frame 5. The means of attaching the bracket-support to the receptacle preferably consists of a split collar 6, made integral with the bracket-support and holding a cup 7. The interior of the cup is screw-threaded, as indicated at 8, to receive the screw-threads of a depending nipple 9, secured by suitable means, as, for example, by soldering, to the bottom of the receptacle 10.

The bottom of the receptacle is preferably secured considerably above the lower edge thereof, so that the cup and nipple and the working parts of the machine generally are

enveloped in a hood 11, which completely protects them from the elements.

12 indicates a valve designed to operate 55 against a seat 13 for regulating the flow of the liquid from the interior of the receptacle into the cup 7. The valve is preferably enclosed within a case 14, having outlet-apertures 15, and is held normally closed by a 60 spring 16, preferably coiled and within a spring-case 17, which forms a separate prolongation of the valve-case 14. The valve is preferably provided with an axial stem 18, which extends beyond the valve on each side, 65 projecting suitable distances to permit of sufficient longitudinal movement through the upper end of the spring-case 17 and the bottom of the cup 7. A sleeve 19 in the cup is preferably provided to prevent leakage of oil around 70 the lower end of the valve-stem, the sleeve being designed to extend above the level of oil which would at any time accumulate within the cup. Any suitable means for lifting the valve-stem and so permitting egress 75 of oil from the receptacle may be employed, as, for example, a trip 20, pivoted in the bracket-frame 14 and having an arm 21 moving in the path of the lower end of the valve-stem. It is obvious that this trip may be 80 moved manually, but I prefer to have it actuated automatically by the machinery to which it is attached. For this purpose, for example, the trip may be made in the shape of a bell-crank lever held normally by the 85 action of the spring 16 in the path of a projection 22, secured to the vane 23 of a windmill. It is well known that the mill is thrown out of gear by swinging the vane into or out of the wind. I prefer to have the projection 22 actuate the trip when the vane is being 90 swung out of gear, because the vane is thrown into gear by its own weight, which might not be sufficient to operate the trip under certain conditions, but it is thrown out by the strength 95 of the operator, which will always be sufficient to overcome any opposing resistance of the trip and the parts which it actuates.

In the foregoing description I have shown mechanism for operating the valve 12 from time to time as may be required to discharge oil into the cup 7. From the cup it is designed to conduct the oil to the different bearing parts of the machine. I therefore provide in

the bottom of the cup a plurality of ducts 24, which preferably consist of short stout tubes projecting below the cup and opening into it through the bottom. These ducts are provided with suitable conduits 25 that respectively carry the lubricator to the different bearings of the machine. I prefer to make these conduits of rigid material, inasmuch as rubber or such flexible conduits are liable to injury from the weather.

It would be difficult in practice to make the conduits without special mechanism operate satisfactorily in connection with movable bearings. For that purpose I prefer to employ in the bottom of each of such conduits a gravity-valve 26, working above a valve-seat 27 and carrying upon the end of its shank 28 a buffer 29. This valve may be called the "auxiliary valve," because it normally retains the lubricant discharged from the cup 7 into the conduit and is lifted by the movement of the mechanism it is designed to lubricate.

In Fig. II of the drawings the movement of operating the auxiliary valve is illustrated. In that figure 30 indicates a pitman having at each end, as usual, bearings 31 and 32. Conducting-tubes 33 and 34 are designed, respectively, to supply lubricating material from the conduits 25 to the bearings. With every complete stroke of the pitman 30 the ends of the conducting-tubes will be brought into proximity with the lower ends of the conduits. Therefore, by providing a grate 35 near the mouth of each conducting-tube the buffer 29 of the auxiliary valve will be lifted sufficiently to discharge a modicum of the pent-up oil within the lower end of the conduit into the flared mouth 36 of the conducting-tube. By this means the movable bearings may be conveniently and certainly oiled as required.

In order to prevent waste of the lubricating material, the conducting-tubes may be made of different diameters, smaller ones being used for lubricating comparatively inactive parts and larger ones employed for more important bearings.

It should be observed that the bottom 10 of the receptacle 1 is concave and that the cup 7 communicates with it centrally. Therefore, the oil in the receptacle will always be discharged into the cup, which is rigidly and inflexibly carried by a strong collar 6.

What I claim is—

1. In lubricating apparatus, the combination with a support, cup, and superimposed receptacle, of mechanism for controlling the egress of liquid from the receptacle to the cup, a conduit adapted to convey liquid from the cup to a bearing, a valve controlling the discharge from the conduit in the lower end thereof, a conducting tube adapted to convey the liquid to a movable bearing, said conducting tube being borne upon a movable part and adapted to operate in its movement

the valve of the conduit, substantially as set forth.

2. In a lubricating apparatus, the combination with a cup and superimposed receptacle, of a valve controlling the egress of the lubricant from the receptacle to the cup, discharge ducts leading from the bottom of the cup, automatically actuated valves in said ducts, a trip beneath said cup operatively connected with the first named valve, and mechanism upon the machine to be lubricated adapted to actuate the trip to permit the egress of the lubricant from the receptacle to the cup and ducts, substantially as specified.

3. In a lubricating apparatus, the combination with a cup and superimposed receptacle, of a valve adapted to control the egress of the lubricant from the receptacle to the cup, a trip operatively connected with said valve, discharge ducts leading from the bottom of the cup, valves in the ducts, and conducting tubes borne upon a movable part adapted to actuate the valves in the ducts, substantially as specified.

4. In a lubricating apparatus, the combination with a duct, of a valve therein provided with a projecting part or buffer, a conducting tube carried upon a moving part and provided with an interior valve actuating grate seated within its upper end whereby the buffer enters the conducting tube and permits of the contiguous relation between the adjacent ends of the duct and tube, substantially as specified.

5. In a lubricating device for wind mills, the combination with a suitable support, of a receptacle and ducts, a valve controlling the egress of the lubricant from the receptacle to the ducts, a movable vane and intermediate mechanism whereby the valve is actuated by the movement of the vane when thrown into the wind to permit the egress of the lubricant from the receptacle to the ducts, and automatically actuated valves in said ducts controlling the egress of the lubricant therefrom to the parts to be lubricated, substantially as specified.

6. In a lubricating device for wind mills, the combination with a suitable support, of a receptacle and ducts, a valve controlling the egress of the lubricant from the receptacle to the ducts, a trip operatively connected with the valve, a movable vane operatively connected with the valve, valves in the ducts, and conducting tubes carried upon moving parts adapted to actuate the valves in the ducts and to convey the lubricant to the part to be lubricated, substantially as specified.

In testimony of all which I have hereunto subscribed my name.

WILLIAM E. SWEET.
